UNITED STATES PATENT OFFICE.

BEMISS N. DAVIS, OF NEW ORLEANS, LOUISIANA.

CAR-UNLOADER.

1,317,484.

Specification of Letters Patent. Patented Sept. 30, 1919.

Application filed February 7, 1918. Serial No. 215,767.

To all whom it may concern:

Be it known that I, BEMISS N. DAVIS, a citizen of the United States, residing at New Orleans, in the parish of Orleans and State of Louisiana, have invented certain new and useful Improvements in Car-Unloaders, of which the following is a full, clear, and exact description.

This invention relates to unloading machinery for gondola cars and other vehicles, the object being to provide a power device or apparatus with which the unloading of a car provided with traps in its bottom and laden with coal, grain, earth, broken stone or other similar material in bulk, can be accomplished with despatch.

The improved apparatus consists essentially of a bridge-like structure under which the loaded car is to be run and its load acted upon by a shovel carried by an overhead truck or carriage, and controlled by means of cables moved by one or more engines or motors.

The invention will be described in detail with reference to the accompanying drawing, in which:

Figure 1 is a side elevation, conventionally illustrated, of the complete device;

Fig. 2 is an end elevation of the same similarly illustrated;

Fig. 3 is a detail of the upper end of the bridge structure;

Fig. 4 is a plan of the carriage or truck;

Fig. 5 is a side elevation of the carriage or truck;

Fig. 6 is a front elevation of the shovel;

Fig. 7 is a side elevation of the shovel; and

Fig. 8 is a section of the shovel on line $x-x$ of Fig. 7.

The frame-work or structure in which the working parts of the device are mounted and operated is a bridge-like affair consisting of two upright frames A and A', respectively, spaced apart to provide for a railway track or other roadway between them, in which the car or other vehicle B may stand while being unloaded. Each of these structures or frames consists of any

suitable design of metallic or other trusses 50 and braces, the parts of which are fastened together and supported upon a suitable foundation. In Fig. 1, each of the upright trusses is represented conventionally by the lines a and these are shown anchored in 55 concrete piers b . The top of each frame A and A' carries overhanging portions c extending toward each other but separated by a space which extends from end to end of the structure. Fig. 3 shows the upper end 60 of this structure in detail, and it illustrates a track-rail d carried by each of the structures and together forming a longitudinal track running the length of the structure and along which a truck or carriage is to 65 be moved. This truck or carriage is illustrated in Figs. 4 and 5 and consists of a frame or body F having two axles each carrying flanged wheels f adapted to run upon the rails d . Suitably mounted in bearings 70 in this truck are two parallel transverse shafts g and h , respectively, the former carrying a pinion g' located in the central plane of the truck and two idlers g^3 each side of the pinion, and also carrying a gear 75 wheel g^2 at one end which meshes with pinion h^2 on the end of shaft h . Shaft h carries a flanged drum h' located at the middle line of the truck.

This truck or carriage which can be moved 80 to any point along the track d by means hereinafter referred to, carries a shovel with which the unloading is accomplished. This shovel is illustrated in Figs. 6, 7 and 8 in detail and is conventionally indicated in full 85 and dotted lines in Figs. 1 and 2 by the letter I. The shovel comprises a blade i and a handle i' , the parts being built up of channels and T-bars riveted together in accordance with best engineering practice 90 to afford strength and proper weight for the work in hand. The handle in cross-section is substantially square as seen in Fig. 8, two of the sides being formed by channel irons i^2 facing each other and separated to form a vertical space i^3 between them. Within this space and attached to one of the channel bars is a vertical rack j ;

the upper and lower ends of the channels are secured together by cross plates i^4 , while the space between the channels is entirely open from end to end of the handle. The 5 handle of the shovel extends up through an opening in the body of the truck with the horizontal shaft g therein passing through the space i^3 in the handle and with the pinion g' on the shaft engaging with the 10 rack j of the shovel handle and the idlers g^3 bearing upon the inner faces of the handle and holding the gear and rack in engagement. It will be seen, therefore, that by rotating the pinion g' , the shovel will be 15 raised or lowered vertically and that in any position to which it may have been adjusted, the shovel is free to swing upon a pivot formed by the engaging teeth of the rack and pinion.

20 The truck or carriage is movable along the overhead rails d by means of a cable l or sprocket chain attached to the truck and passing over sheaves l' and l^2 at each end of the structure, the sheave l^2 being on the same shaft with a worm gear driven by a reversible engine L ; the worm and gear affording a lock to hold the truck at any point to which it may have been moved. The shovel i is lowered by gravity and elevated 25 by power supplied by a second engine M . A cable o runs from one of the drums of the engine over a sheave o' at one end of the structure, thence to the truck where it is wound upon the drum h' . Pulling upon 30 this cable by the engine rotates shaft h , pinion h^2 , gear g^2 and the pinion g' , and the latter engaging with the rack in the shovel handle lifts the shovel. Releasing the cable at the drum of the engine allows the 35 shovel to fall by its own weight. To the front and back faces of the shovel are attached two other cables, respectively, p and q which lead over suitable guide pulleys at the respective ends of the structure to two 40 other drums of the engine M . By causing the engine to wind up the cable on one of these drums while letting out the cable on the other, the shovel is caused to swing forward or backward as the case may be and 45 to reverse its swing by correspondingly reversing the action of the two drums.

50 The device is used in the following manner:

A loaded gondola car having central openings or pockets in its floor is moved to a 55 mid position under the structure, as shown in Fig. 1. If the contents of the car does not immediately start to flow through the openings, the truck is moved along the track 60 until the shovel is poised directly above the pocket, whereupon it is allowed to suddenly drop upon the load to start the flow. If the load is frozen or for any reason does not at once commence to flow out, the shovel

can be raised and dropped repeatedly until 65 the flow is free. When the middle portion of the load has emptied, the truck is moved toward one end of the car where the shovel is allowed to drop and bury itself in the load and is then dragged toward the center 70 of the car to push the load toward the opening. This is repeated until the contents of the car at one end has been emptied, whereupon the truck is shifted to bring the shovel over the opposite end of the car where the 75 same operations are repeated. Skilful operators at the two engines can in this manner very quickly unload a gondola car.

It will be understood that other mechanism for raising and lowering the shovel may 80 be used in place of the pinion and rack described without departing from the spirit of my invention.

I claim:

1. An unloader for a car having openings 85 in its floor, comprising a structure provided with an overhead track, a carriage adapted to run on said track in the same direction of movement as the direction of movement of the car below, a shovel pivotally mounted 90 upon said carriage and comprising a rigid two-faced blade and handle in alinement with one another, and means for rocking the shovel about its axis to permit the shovel while so rocked to gradually sweep the contents of the car through its floor openings 95 from both ends of the car.

2. An unloader for a car having openings in its floor, comprising a structure having an overhead track, a carriage adjustable 100 along said track, a winding drum and pinion mounted on said carriage and geared together, a shovel having a two-faced blade and handle in alinement with one another and provided with a rack in engagement 105 with said pinion, whereby said shovel may be raised and lowered, and swung to and fro to permit the shovel while so rocked to sweep the contents of the car through its floor openings from both ends of the car. 110

3. A car unloader comprising a carriage adapted to move along a track, a shovel suspended upon said carriage and having a handle provided with a longitudinal passage, a rack extending along one side of said 115 passage, a shaft carried by said carriage and extending through the passage in the handle, a pinion on said shaft engaging said rack, and idlers on said shaft for guiding said handle in its pivotal movement about 120 said shaft.

4. An unloader for a car having openings in its floor, comprising a structure provided with an overhead track extending lengthwise of the car, a carriage on said 125 track, a shovel carried by the carriage and mounted for pivotal movement relative to the carriage, and means for positively

swinging the shovel in both directions about its pivotal axis.

5. An unloader for a car having openings in its floor, comprising a structure provided with an overhead track extending lengthwise of the car, a carriage on said track, a shovel carried by the carriage and mounted for both pivotal and vertically reciprocatory movement relative to the carriage, means for imparting reciprocatory

movement to the shovel, and means for positively swinging the shovel in both directions about its pivotal axis.

In witness whereof I subscribe my signature in the presence of two witnesses.

BEMISS N. DAVIS.
